UNITED STATES PATENT OFFICE.

EDMUND SCHERFF, FRANZ REHDORFF, AND CARL OTTOW, OF BERLIN, GERMANY; SAID OTTOW ASSIGNOR TO SAID SCHERFF AND REHDORFF.

SELF OPENING OR CLOSING UMBRELLA.

SPECIFICATION forming part of Letters Patent No. 616,977, dated January 3, 1897.

Application filed September 18, 1897. Serial No. 652,098. (No model.)

To all whom it may concern:

Be it known that we, EDMUND SCHERFF, FRANZ REHDORFF, and CARL OTTOW, subjects of the King of Prussia, German Emperor, and residents of Berlin, in the Kingdom of Prussia, German Empire, have invented 5 certain new and useful Improvements in Self-Opening or Self-Closing Umbrellas, of which the following is an exact specification.

This invention relates to improvements in that kind of self-opening and self-closing umbrellas described in the United States Letters Patent No. 604,495, dated May 24, 1898, and has for its object to effect an improvement 10 in our above-named application for Letters Patent in the following points:

First, in the present application we have attained an improved bearing for the inner tube, which now slides to and fro upon the 15 interior of the outer tube, this being in the above-named previous construction not possible, as the spring was between the two tubes.

Our second improvement in the present application consists in locating the spring within the inner tube instead of, as above indicated, between the two tubes. Hereby, as 20 is apparent, we cause the thickness of the spring-wire to be independent of the tube-walls, or, more precisely, independent of the 25 amount of space between the said tube-walls.

Our third improvement in the present application consists in doing away with the pin *d'* named in the previous construction, 30 by which pin the outer tube was often fretted through.

We attain these objects by the mechanism represented in the accompanying drawings, in which similar letters denote similar parts 35 throughout the several views, and in which—

Figure 1 is a longitudinal section through our improved umbrella. Fig. 2 is a similar section, the parts being in another position. Fig. 3 shows the tubes forming the body of 40 the umbrella without the cloth-supporting and other rods or ribs, said tubes and their adjacent parts being drawn on a larger scale and some portions of them being broken out in order to reduce the length of the figure. Fig. 4 shows the umbrella opened.

The handle *r*, Figs. 1, 2, and 4, of the umbrella is fixed to a tube *a*, Figs. 1 to 4. Within the latter is fastened a cylindrical block *f*, which has the purpose of supporting the coil-spring *e*. Above the latter a tube *b*, 55 or, more precisely, a portion thereof, is situated within the tube *a*, and may be displaced within the latter. The inner end of the tube *b* is closed by means of a block *f'* and rests on the spring *e*, which tends constantly to move the tube *b* out of the tube *a*.

To the block *f* is fastened a rod *g*, which freely penetrates the block *f'* and has to its end fastened a stop *f''*, the latter having the purpose to limit the outward movement of 60 the tube *b*.

The upper end of the tube *b* carries the top notch *c* for the cloth-supporting ribs *d* and the braces *k*, that are connected to a set of auxiliary stretchers *i*. The latter are hinged 70 at one end to small slides *q*, arranged displaceably upon the ribs *d*, and are hinged at their other ends to the upper end of a tube *h*, that encompasses the tubes *a* and *b*. The other end of the tube *h* is provided with an 75 aperture, through which takes a catch *o*, attached to the tube *a*. The tube *h* carries a catch *l*, which takes into the projecting margin *n* of the runner *m*. This runner is provided with a bearing-disk *w*, and a similar 80 disk *x* is secured to the upper end of the tube *h*. The one end of the auxiliary stretchers *p*, above mentioned, is held by the disk *w* of the runner *m*, the other ends of said stretchers *p* being hinged to the small slides *q*, above 85 mentioned.

Assuming the umbrella to be in a closed position, Fig. 1, the spring *e* would be in tension and would be prevented from forcing the tube *b* in an outward direction—*i. e.*, from 90 opening the umbrella—by the catch *l* taking behind the projection *n* of the runner *m*. The tube *h* is prevented from moving along tube *a* by means of a catch *o*. If, however, the catch is released, the runner *m* will glide 95 along the tube *h* under the pressure of the spring *e*, in that the force of the latter is transmitted to said runner *m* by means of the braces *k*, and the stretchers *i* and *p* being allowed to rise also the cloth-supporting ribs 100

d are allowed to rise and the umbrella is thus opened.

There are no special means for keeping the umbrella in its opened position, in that the 5 spring *e* after having effected said opening is not yet fully released. There remains in said spring as much force as is requisite for making the opened umbrella able to withstand the pressure of even a strong wind.

10 Before describing the manner of closing the umbrella we wish to call attention to the fact that in order to bring the parts *d*, *k*, *i*, and *e* into their former relative position it is not necessary to move these parts in exactly 15 the reverse way, but the same result may be obtained by moving the auxiliary stretchers *i* around their points of connection with the braces *k*. This may be obtained by uncoupling the tube *h* from tube *a* by means of the 20 catch *o* and then letting the tube *h* glide along the tube *a* in a direction to the top notch *c* of the tube *b*. It should be borne in mind that the rods *d* and *p* tend to turn the rods *i* around the points of connection of said 25 rods *i* with the rods *k*. The weight of the tube *h* is not sufficient to withstand the counteraction of the rods *d* and *p* and of the longer arms of the rods *i*, together with the slides *q* and the cloth. If, therefore, the tube *h* is un- 30 coupled from the tube *a*, the umbrella is instantly closed and all the parts assume the position shown in Fig. 2. On the closing of the umbrella the pawl *l* has automatically taken behind the projecting margin *n*, so as

practically to couple the tube *b* to the tube 35 *h*, and both these tubes are now displaced along the tube *a* in the direction of the handle, so as to compress or strain the spring *e*, and all the parts are finally fixed in position by means of the pawl *o* coupling the tube *h* 40 to the tube *a*. The umbrella is now fit for being used in the same way as before described.

Having thus fully described the nature of this invention, what we desire to secure by 45 Letters Patent of the United States is—

In self-opening and self-closing umbrellas or parasols, the combination of the tube *a* fastened to the handle *r*, with the tube *b* arranged displaceably within the former, the 50 tube *h* arranged displaceably upon said tube *a*, the block *f* fastened within said tube *a* and the block *f'* fastened to the inner end of tube *b*, a coil-spring *e* arranged between the blocks *f* and *f'*, a rod *g* fastened to said block *f*, and pen- 55 etrating block *f'*, a stop *f''* fastened to the end of said rod *g*, and the runner *m*, auxiliary stretchers *i* stretchers *p*, and ribs *d*, as and for the purpose set forth.

In testimony whereof we have signed this 60 specification in the presence of two subscribing witnesses.

EDMUND SCHERFF.
FRANZ REHDORFF.
CARL OTTOW.
